UNITED STATES PATENT OFFICE.

LOUIS MANDEL, OF CHICAGO, ILLINOIS,

CONVERTIBLE MOTION-PICTURE MACHINE.

1,191,329.

Specification of Letters Patent. Patented July 18, 1916.

Application filed April 16, 1915. Serial No. 21,638.

To all whom it may concern:

Be it known that I, LOUIS MANDEL, a citizen of the United States, residing at Chicago, in the county of Cook and State of Illinois, have invented certain new and useful Improvements in Convertible Motion-Picture Machines, of which the following is a specification.

This invention relates to improvements in motion picture machines adapted to be used for photographing pictures upon a strip in rapid succession, and subsequently employed for projecting the pictures upon a screen, the machine being also adapted to be used for photographing what is known as "still" pictures and subsequently projecting the "still" pictures upon a screen.

A further object is to provide an improved machine of this character also adapted to be used for printing the positive film from the strip containing the pictures to be printed.

A further object is to provide an improved compact device of this character, which will be of small dimensions, and so constructed that the operating mechanism may be readily removed from the casing as a single unit, and as readily inserted into the casing, the frame of the operating mechanism also serving to divide the casing into three compartments, two of which compartments being adapted to receive and hold the film rolls.

To the attainment of these ends, and the accomplishment of other new and useful objects, as will appear, the invention consists in the features of novelty in substantially the construction, combination and arrangement of the several parts hereinafter more fully described and claimed and shown in the accompanying drawings illustrating the invention and in which:

Figure 1 is a rear elevation of an improved machine of this character, constructed in accordance with the principles of this invention, with the casing open and with parts broken away. Fig. 2 is a longitudinal sectional view taken on line 2—2, Fig. 1. Fig. 3 is a view of the mechanism removed from the casing and as taken on line 3—3, Fig. 1. Fig. 4 is a vertical longitudinal sectional view taken on line 4—4, Fig. 2. Fig. 5 is a view similar to Fig. 3, taken from the opposite side of Fig. 3. Fig. 6 is a view taken on line 6—6, Fig. 1, and showing the apparatus adjusted for the purpose of printing.

Referring more particularly to the drawing, the numeral 10 designates generally an inclosing casing, having an open side which is closed by a closure 11. The casing is provided with an opening 12 in its wall 13 and connected with the opening is a lens 14, preferably located inside of the casing. The wall 13 of the casing is provided with open grooves 15, while the side walls are provided with grooves 16, 17.

The operating mechanism is arranged within the casing and comprises a supporting structure having a wall 18 and end walls 19 arranged perpendicularly thereto, at the ends of the wall 18, and side walls 20, 21. The structure thus formed, is adapted to be inserted into the casing, so that the edges of the walls 19, will enter the grooves 15, 16 and 17, and the structure is of such a size as to extend across the casing, so that the walls 19 will divide the casing into two end compartments, 22, 23 and an intermediate compartment 24.

Mounted upon the structure thus formed and supported in any suitable manner, is a rotatable toothed element or sprocket wheel 25, a portion of which projects through a suitable opening 26a in the wall 18 of the structure. Connected with the shaft of this sprocket wheel is a Geneva element 26, and a coöperating Geneva element 27, which latter is provided with the operating pin 28, and is connected with a shaft 29 which has secured to it a gear 30. The gear 30 meshes with a gear 31, which latter is connected with a shaft 32, and mounted upon the shaft 32 is a pulley 33, for a purpose to be herein-after set forth. The gear 31 in turn meshes with a gear 34. This gear 34 meshes with a gear 35 which has connected with it to operate therewith, a gear 36, and the gear 36 in turn meshes with another gear 37, and these series of gears constitute a train of gears by means of which the Geneva element is rotated and this element in turn rotates the Geneva element 26 and consequently, the sprocket 25, to feed the flexible strip 38 across the field of the lens 14.

Supported by the walls 19 of the supporting structure are brackets 39, 40, upon which are mounted the reels 41, 42, which hold the flexible strip 38, and the bracket 40 and reel 42 are located in the compartment 22, while the bracket 39 and reel 41 are located in the compartment 23.

The gear 37 has connected with it a socket

43 (see particularly Fig. 3), while the gear 34 has connected with it, a socket 44, and a similar socket 45 is connected with the gear 30. These sockets are adapted to successively receive a crank (not shown) and which is inserted into the respective sockets from the outside of the casing, thereby rendering it possible to impart a variable speed of rotation to the sprocket 25 to vary the speed of the movement of the flexible strip 38 at the will of the operator, and at different points in the train of gears.

Connected with the shaft 46, upon which the reel 41 is rotatably mounted, is a pulley 47 which is mounted in alignment with the pulley 33, and a flexible belt 48 passes over these pulleys and through suitable apertures in the wall 19 of the support, so that when the sprocket 25 is rotated to feed the film from the reel 42, the film will be wound upon the reel 41.

A balance wheel 49 is connected with the shaft 29, upon which the reel 41 is rotatably mounted, for the purpose of insuring a steady movement.

25 The wall 18 of the supporting structure is provided with an aperture 50 which is mounted in alignment with an aperture 51 in the closure 11, and this aperture 51 is preferably of a size somewhat larger than the aperture 50 and is provided with a conical shield 52 for directing the light into the aperture 50. Supported by the wall 18 is a gate or guide 53 which is pivotally connected thereto as at 54 and is provided with an aperture 55 arranged in alignment with the apertures 50, 51, and a catch 56 is also provided for holding the gate closed. The flexible strip 38 passes between the gate 53 and the wall 18 so as to pass across the registering openings 50, 51, 55 and in order to hold the strip in position, and against the sprocket wheel 25, rollers 57 are provided for that purpose. The gate is provided with cut away portions 58, 59, in its upper and lower edges and through which portions the flexible strip is adapted to pass, under certain conditions. A shutter 60 is also provided and mounted upon the supporting structure. The shaft 61 of the shutter is mounted in suitable bearings and has connected with it a bevel gear 62, which latter meshes with a bevel gear 63, the gear 63 being connected to operate with the gear 35, so that when the mechanism is actuated to feed the flexible strip, the shutter 60 will be correspondingly rotated.

Finders 65, 66 are provided, and the opening 51 in the closure 11 is closed by means of a temporary closure 64, and this temporary closure is employed when it is desired to use the apparatus for photographing purposes, the feeding mechanism being operated by means of a crank from any point desired in the train of gears. Under ordinary conditions of sufficient light, and when motion

or animated pictures are desired, the feeding mechanism may be operated from the gear 37, but when there is not sufficient light and it is desired to give a little longer exposure, to the views, the feeding mechanism is operated from the gear 34 in the train. When it is desired to photograph what is known as "still" pictures, that is, by advancing the flexible sensitized strip the distance of one picture or view, the feeding mechanism is operated from the shaft 29 by placing the crank in the socket 45, and one complete revolution of the gear 30 will be sufficient to advance the sensitized strip the proper distance.

When it is desired to use the apparatus for subsequently projecting the picture on to a screen, the temporary closure 64 is removed and in its place is arranged an attachment 67 which is provided with a condenser lens 68 and which lens is mounted in alignment with the registering openings 51, 55, 50 and in order to provide sufficient light for the purpose of projecting pictures, a source of light 69 is provided, which is preferably arranged within a casing 70, the latter being adjustably connected with the attachment 67, to be moved toward or away from the condenser lens 68.

The printing is accomplished by feeding the sensitized strip 38 through the apparatus in the manner as already described, and the objects to be printed upon the strip 38 are arranged upon another flexible strip 71, which is fed from a reel 72 arranged on the outside of the casing and held in position by means of a detachable support 73. The flexible strip 71 is then passed into the casing through an opening 74 which latter is closed by a flexible closure 75, that contacts with the flexible strip as it passes through the opening, to prevent the entrance of light at that point. This opening 74 is arranged in close proximity to the cut away portion 58 of the gate 53, as shown more clearly in Fig. 6, and the flexible strip then passes over the adjacent roller 57 in contact with the sensitized strip 38, through the gate, over the sprocket 25 through the cut away portion 59 in the gate and then through another opening 76 again to the outside of the casing and which opening 76 is closed by a flexible closure 77, that contacts with the flexible strip to prevent the entrance of light into the casing. With the two strips thus arranged, it will be seen that when the feeding mechanism is operated, both of the flexible strips will be simultaneously fed across the field of the condenser, while the sensitized strip is maintained within the casing and the other strip will be passed from the outside of the casing into the casing to be printed from and then again to the outside.

If desired and in order to support the flexible strips in contact with each other ad-

5 jacent the opening 50, a removable support 78, (see Fig. 6), may be employed at that point. A supplemental gate 53^a is connected with the main gate 53, by means of bolts 53^b and springs 53^c are also provided for yieldingly holding the supplemental gate against the flexible strip so that the supplemental gate will yield to compensate any irregularity in the flexible strip.

10 Should it be desired, the condenser attachment 67 and the source of light 69 may be omitted and printing may be accomplished either directly from the sun or the opening 51 may be arranged and held in 15 alinement with any suitable source of light. Printing may also be done for "still" pictures, by operating the mechanism from the gear 30 and when it is desired to project the "still" pictures, the feeding mechanism may 20 be operated from the same point.

With this improved construction, it will be manifest that the apparatus is convertible for a number of different uses, thereby combining in a single construction a multiplicity of devices. It will also be manifest that 25 all of the operating mechanism is mounted upon a supporting structure, which is removably held within the casing, and when it is desired, this structure, the operating 30 mechanism, the shutter, and reels for the flexible strips may be bodily removed from the casing as a single unit.

Obviously many changes may be made in 35 the details of construction and in the combination and arrangement of the several parts without departing from the spirit of this invention.

What is claimed as new is:

1. In a device of the character described, 40 a casing having an open side, a lens arranged in one of the walls of the casing, the side and front walls of the casing being provided with registering open grooves, a supporting frame embodying a face wall and end walls arranged perpendicularly thereto, said face wall being provided with an aperture adapted to register with the lens opening, film feeding mechanism mounted upon the said structure, intermediate the 45 said end walls, film reel supports, supported by the end walls of the said frame, said frame and the supported mechanism being freely removable from and adapted to be inserted in the casing as a self-contained unit, the said grooves in the casing walls receiving the edges of the end walls of the frame to divide the casing into light tight compartments, and a closure for the casing.

2. In a device of the character described, 50 a casing having an open side, a lens arranged in one of the walls of the casing, the side and front walls of the casing being provided with registering open grooves, a supporting frame embodying a face wall and end walls arranged perpendicularly thereto,

said face wall being provided with an aperture adapted to register with the lens opening, film feeding mechanism mounted upon the said structure, intermediate the said end walls, film reel supports, supported by the 55 end walls of the said frame, a gate pivotally connected with said face wall and through which gate a flexible strip passes, said frame and supported mechanism being freely removable from and adapted to be inserted in the casing as a self-contained unit, the said grooves in the casing walls receiving the edges of the end walls of the frame to divide the casing into light tight compartments and a closure for the casing.

3. In a device of the character described, a casing having an open side, a lens arranged in one of the walls of the casing, the side and front walls of the casing being provided with registering open grooves, a supporting frame 85 embodying a face wall and end walls arranged perpendicularly thereto, said face wall being provided with an aperture adapted to register with the lens opening, film feeding mechanism mounted upon said structure, intermediate the said end walls, film reel supports, supported by the end walls of the said frame, said frame and supported mechanism being freely removable from and adapted to be inserted in the 90 casing as a self-contained unit, the said grooves in the casing walls receiving the edges of the end walls of the frame to divide the casing into light tight compartments, a closure for the casing, said closure having an 100 opening adapted to register with the lens opening, and interchangeable attachments adapted to be attached to the said closure adjacent the opening therein.

4. In a device of the character described, 105 a casing having an open side, a lens arranged in one of the walls of the casing, the side and front walls of the casing being provided with registering open grooves, a supporting frame embodying a face wall and end walls arranged perpendicularly thereto, said face wall being provided with an aperture adapted to register with the lens opening, film feeding mechanism mounted upon the said structure, intermediate the said end walls, film reel supports, supported by the end walls of the said frame, said frame and the supported mechanism being freely removable from and adapted to be inserted in the casing as a self-contained unit, the said grooves in the casing walls receiving the edges of the end walls of the frame to divide the casing into light tight compartments, a closure for the casing, and a lens casing connected with the lens, said lens casing being disposed entirely within the plane of the outer face of the adjacent wall of the first said casing.

5. In a device of the character described, 120 a casing having an open side, a lens arranged in one of the walls of the casing, the

4
 side and front walls of the casing being provided with registering open grooves, a supporting frame embodying a face wall and end walls arranged perpendicularly thereto,
 5 said face wall being provided with an aperture adapted to register with the lens opening, film feeding mechanism mounted upon the said structure, intermediate the said end walls, film reel supports, supported by the end
 10 walls of the said frame, said frame and the supported mechanism being freely removable from and adapted to be inserted in the casing as a self-contained unit, the said grooves in the casing walls receiving the edges of the end walls of the frame to divide the casing into light tight compartments, a closure for the casing, said film feeding mechanism embodying a train of gears and means whereby said train of gears may be
 15 actuated at different points in the train to vary the speed of movement of the flexible strip, and a shutter also mounted upon the support.

6. In a device of the character described, a
 20 casing having an open side, a lens arranged in one of the walls of the casing, the side and front walls of the casing being provided with registering open grooves, a supporting frame embodying a face wall and end walls

arranged perpendicularly thereto, said face 30 wall being provided with an aperture adapted to register with the lens opening, film feeding mechanism mounted upon the said structure, intermediate the said end walls, film reel supports, supported by the end 35 walls of the said frame, said frame and the supported mechanism being freely removable from and adapted to be inserted in the casing as a self-contained unit, the said grooves in the casing walls receiving the 40 edges of the end walls of the frame to divide the casing into light tight compartments, a closure for the casing, said casing having spaced openings through which a second flexible strip may be fed through the casing, 45 flexible means forming closures for the last said openings and with which means the flexible strip contacts and means exterior of the casing for supporting a reel of said flexible material.

50 In testimony whereof I have signed my name to this specification, in the presence of two subscribing witnesses, on this 13th day of April A. D. 1915.

LOUIS MANDEL.
